US0D1057581S

(12) **United States Design Patent** (10) **Patent No.:** **US D1,057,581 S**
(45) **Date of Patent:** **** Jan. 14, 2025**

(54) **DOORBELL**

(71) Applicant: **Google LLC**, Mountain View, CA (US)

(72) Inventors: **Hae rim Jeong**, San Francisco, CA (US); **Sung Bai**, San Jose, CA (US); **Maj Isabelle Olsson**, Sunnyvale, CA (US); **Albert JK Lee**, San Francisco, CA (US); **Meng Tse Tsai**, New Taipei (TW); **Leslie Marie Welborn Greene**, Belmont, CA (US)

(73) Assignee: **Google LLC**, Mountain View, CA (US)

(**) Term: **15 Years**

(21) Appl. No.: **29/847,205**

(22) Filed: **Jul. 22, 2022**

(51) **LOC (15) Cl.** **10-05**

(52) **U.S. Cl.**

USPC **D10/118.2**; D10/118

(57) **CLAIM**

The ornamental design for a doorbell, as shown and described.

DESCRIPTION

FIG. 1 is a top, front, right side perspective view of a doorbell showing our new design;

FIG. 2 is a top, back, left side perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines in the drawing figures are for the purpose of illustrating portions of the doorbell that form no part of the claimed design.

1 Claim, 4 Drawing Sheets
